UNITED STATES PATENT OFFICE.

JOHN HRABAK, OF KERMIT, NORTH DAKOTA, ASSIGNOR, BY MESNE ASSIGNMENTS, OF ONE-HALF TO L. A. O. KNOPH, OF NOONAN, NORTH DAKOTA.

MUSIC-STAND.

1,067,609.

Specification of Letters Patent.

Patented July 15, 1913.

Application filed January 15, 1913. Serial No. 742,208.

To all whom it may concern:

Be it known that I, JOHN HRABAK, of Kermit, in the county of Divide and State of North Dakota, have invented certain new 5 and useful Improvements in Music-Stands, of which the following is a specification.

My present invention relates to folding music stands, my object being to provide a stand which may be conveniently and 10 readily folded into a compact structure of substantially reduced size, whereby to render its transportation more ready and convenient.

In the accompanying drawings which 15 illustrate my invention, Figure 1 is a front elevation illustrating the music stand unfolded and in operative position; Fig. 2 is a side elevation, the lower leg portion being broken away; Fig. 3 is an enlarged vertical 20 section through the intermediate portion of the stem of the stand; Fig. 4 is a detail transverse section taken substantially on the line 4—4 of Fig. 3; Fig. 5 is a front elevation, on an enlarged scale, of the upper folding 25 music frame; Fig. 6 is a bottom plan view thereof; Fig. 7 is a front elevation of the music stand folded for transportation; Fig. 8 is a detail vertical section through the lower stem portion and the leg guide; and, 30 Fig. 9 is a transverse section taken substantially on the line 9—9 of Fig. 8.

Referring now to these figures, the main upright stem of my improved stand embodies an intermediate section or main 35 handle section A, an upper section A' and a lower section A², the intermediate section A having a handle a and a tubular portion a' into which the lower end of the upper section A' is telescopically disposed. As 40 seen clearly in Fig. 3, the lower end of the intermediate section A is bifurcated and between the bifurcations is pivoted the upper end of the lower section A² at a², the lower end of the lower section A² having a circular enlargement a³ to which are pivoted the 45 depending radial diverging legs B.

A main operating lever C is intermediately pivoted at c to the intermediate stem section A and extends substantially at right angles thereto, this lever being provided 50 with a handle c' at one end and an upwardly extending lug c² between the handle c' and its pivot c. Pivoted connected to the lugs c², at its lower end, and to a portion of the 55 upper stem section A', at its upper end, is

a connecting link C', whereby when the handle c' of the lever C is depressed from the position shown in Fig. 1, the upper stem section A' is caused to lower and extend downwardly within the tubular portion a' 60 of the intermediate stem section A. In like manner a connecting link C² is pivotally united at its upper end to the opposite extremity of the lever C and is pivotally united at its lower end to the lower stem 65 section A² at a point intermediate the ends of the latter, whereby when the handle c' is depressed and the upper stem section A' lowered as just described, the lower stem section A² will be moved angularly upon its 70 pivot a², all as clearly seen in Fig. 7.

The lower end of the lower stem section A² is provided with a longitudinal bore into which the stem b of the leg guiding block B' is projected, this block B' being disposed 75 within and between the legs B below the lower end of the stem section A² and being provided with U-shaped members b' surrounding the several legs whereby when the block is lowered with respect to the stem 80 section A², the legs B will be drawn inwardly toward one another. In order to effect this movement simultaneously with the folding of the main stem section, a link B² is pivotally connected at its lower end to 85 the block B' and at its upper end to the connecting link C² at a point intermediate the ends of the latter, whereby when the lower stem section A² is moved angularly to 90 the position shown in Fig. 7, the block B will 90 be forced away from the lower stem section A² and the legs B at the same time drawn inwardly to the position shown in dotted lines in Fig. 8.

The upper end of the stem section A' is 95 rigidly connected to the central inclined bar D of the inclined music holding frame embodying side portions D' and D² which are pivotally connected at d to the upper and lower ends of said central bar D. To the 100 lower portions of the frame sides D' and D² are pivotally connected links d' and d², these links being pivotally united at their inner ends in longitudinal alinement with the central bar D by means of a member d³ 105 to which the upper end of an actuating link D³ is pivotally connected, the lower end of said link d³ being pivotally connected at d⁴ to the upper end of the intermediate stem section A whereby when the upper stem 110

section A' is lowered, the connected ends of the links d' and d² will be forced upwardly, folding the frame sides D' and D² forwardly upon one another, as indicated by 5 the arrows in Fig. 6 and as particularly shown in the folded position in Fig. 7.

Thus from the foregoing it will be seen that both the upper and lower portions of the main stem are folded with respect to the 10 intermediate portion, and the legs and sheet holding frame folded at the same time, all of these movements being effected through connections from a single actuating lever and being such as to produce a compact 15 structure adapted to ready and convenient transportation as desired.

I claim:—

1. In a folding music stand, the combination of a main stem embodying an intermediate section, an upper section having a movable connection with the intermediate section and carrying a folding sheet supporting frame at its upper end, and a lower section also having a movable connection with 25 the intermediate section and carrying folding legs at its lower end, and a lever having connection with the intermediate section and provided with connections whereby to fold all of the parts upon a single movement 30 thereof.

2. A folding music stand embodying an upright stem having an intermediate portion, an upper portion slidable with respect to the intermediate portion, and a lower 35 portion pivoted to the intermediate portion, a transverse lever intermediately pivoted to the intermediate stem portion, and links connecting the upper and lower stem sections with portions of the said lever upon 40 opposite sides of its pivot whereby to cause movement of the upper and lower stem sections when the lever is rocked upon its pivot.

3. In a folding music stand, the combination 45 of a vertical stem embodying an intermediate section, and upper and lower sections, a folding music frame carried by the upper section, the lower section being pivotally connected at its upper end to the lower

portion of the intermediate section, a lever 50 carried by the intermediate section, a connecting link between the lever and the lower stem section whereby to cause the latter to swing upwardly toward the intermediate section when the lever is actuated, depending divergent legs pivotally connected at their upper ends to the lower stem section, a guide block disposed within the said legs and having guide members encircling the several legs, and an actuating link extending 60 between the said connecting link and the said guide block whereby to cause movement of the latter with respect to the lower stem section and thus draw the legs together when the lower stem section is swung angularly upon the intermediate stem section.

4. In a music stand, the combination of an upright stem embodying an intermediate section, a lower section carrying supporting legs, and an upper section having a sliding 70 telescoping engagement with a portion of the intermediate section, a lever carried by the intermediate section, a link pivotally connecting the lever with the said upper section whereby to move the same downwardly 75 to telescoped position within the intermediate section, an upper music supporting frame embodying a center bar rigidly connected to the upper end of the upper stem section, and side portions pivotally connected 80 to the said center bar, links pivotally connected together at their inner ends and having their outer ends pivotally connected to the said side portions of the music frame, a member pivotally connecting the said inner ends of the said links, and an actuating link pivotally connected at its upper end to the said member and at its lower end to the intermediate stem section whereby when the upper stem section is telescoped, the 85 side portions of the music frame will be 90 folded against one another substantially as described.

JOHN HRABAK.
